ROLLER TOWEL CABINET CONSTRUCTION

Ben H. Belenson, Detroit, Mich., assignor of one-tenth to Rankin P. Peck and Fred B. Radley, Detroit, Mich.

Application March 25, 1935, Serial No. 12,758

2 Claims. (Cl. 312—38)

This application relates to improvements in roller towel cabinet constructions.

The principal object is the provision of a roller towel feed control and locking construction which is novel and eminently satisfactory for the purposes for which it is designed.

Roller towel cabinet constructions have been designed upon the principle of freeing the towel upon the actuation of a plunger; the towel when thus freed is manipulable by direct pull upon a previously soiled front portion of an exposed loop thereof by the hands of the user. In order to limit the length of clean toweling that can be thus pulled out when the towel is freed, and thus in order to determine the length of clean toweling that is supplied for each plunger actuation, a locking mechanism is incorporated. The locking mechanism here disclosed includes a rough surfaced locking or measuring roller, over which the supply of clean toweling is pressed as it passes on its way from the clean roll to the point outside the box where it forms the exposed loop. In addition, there is a second rough surfaced roller, and this one cooperates with a winding spool to wind or take up the soiled toweling into a soiled roll. The measuring and take up rollers are provided with sprocket wheels connected by an endless sprocket chain, and the latter carries stop means cooperating with a locking cam whereby travel of the chain, the rollers, and the towel controlled thereby will be under the control of the locking cam. The amount of toweling supplied is determined by the length of the endless chain between stops. If but one stop is used on the endless chain the length of toweling supplied would equal the sum of half the diameters of the rollers plus twice the center to center distance between them; if it is desired to have the length of toweling supplied equal to a fraction of that length, two or more stops may be positioned on the chain, equally spaced around the latter, and the distance between stops will determine the length of toweling supplied. The locking cam is freed for releasing the chain and permitting it and the rollers to move when the front part of the exposed loop is pulled down from the cabinet by actuation of the plunger. Immediately after the cam is released and the front part of the exposed loop is pulled down, the locking cam is automatically reset into locking position so as to be engageable by the stopping means carried by the endless chain, such engagement terminating the movement of the chain, the rollers, and the towel, and terminating the feeding of clean toweling.

The details of construction shown in the appended drawings and forming the cabinet construction heretofore outlined will best be understood upon reference to the specification which follows, for an understanding of which reference should be had to the appended drawings. In these drawings,

Fig. 1 is a front view of the cabinet in condition for use;

Fig. 2 is a view as if from the right of Fig. 1;

Fig. 3 is a view similar to Fig. 1 but showing the cabinet with its door removed;

Fig. 4 is a section as if on line 4—4 of Fig. 1;

Figs. 5 and 6 are sections as if on lines 5—5 and 6—6 of Fig. 3;

Fig. 7 is a section as if on line 7—7 of Fig. 6;

Fig. 8 is a top plan view of the machine per se;

Fig. 9 is a section as if on line 9—9 of Fig. 1;

Fig. 10 shows coin control parts;

Fig. 11 is a section as if on line 11—11 of Fig. 5;

Figs. 12—14 show operating parts of the machine in chain-stopping, chain-released, and locking cam resetting positions, respectively;

Fig. 15 shows the chain of the machine.

Within the box are sprocket wheels 44—45, the former being fixed to and on the end of locking or measuring roller 29 and the latter being fixed to and on the end of winding or take up roller 30. A multi-link sprocket chain 46 of endless form connects these sprocket wheels so that the two rollers 29 and 30 are interlocked to each other.

For locking the chain and thus for locking the rollers 29—30 against movement and consequently locking the towel against movement, the chain is provided with a stop means 47 in the nature of a lug formed as one of the links of the chain and projecting from the remainder of the links. This stop is adapted to cooperate with the stop and reset portions 48 and 49 of a locking cam 50 formed as a bell crank 50, pivoted at 51 and having an upwardly extending release part 52.

It is observed that if the towel is free and when the front portion 53 of the exposed loop of the towel is pulled down, the rollers 29 and 30 and their sprockets 44 and 45 are rotated; consequently chain 46 will move until its stop 47 strikes stop 48 of the locking cam 50, whereupon further movement of the chain, the sprockets, the rollers, and the towel is prohibited. When the upwardly projecting release part 52 of the locking cam is moved in a manner that will later be described, stop portion 48 of the locking cam 50 will move away from the stop 47 of the chain which is in engagement there-

with, and thereupon pull upon portion 53 of the exposed loop of the towel will cause the rollers, sprockets, and chain to move until chain-stop 47 again engages the stop portion 48 of the locking cam. The travel of the stop 47 determines the length of towel supplied upon each actuation thereof.

It is observed that the locking cam is reset automatically to stop position after having been released by the engagement of stop 47 of the chain with reset portion 49 of the locking cam, the engagement taking place immediately after the chain had been started to move by pulling down of portion 53 of the towel and after its stop 15 47 had left stop portion 48 of the locking cam.

To maintain the locking cam in the reset position after reset in this fashion has taken place, a spring 54 is provided, and the same engages a shoulder pin 55 on the release extension 52 of the locking cam 50 to hold the latter in reset position after it had once been moved there by the engagement of stop 47 and reset portion 49.

Any means might be utilized to engage release extension 52 of the locking cam 50 for release of the machine parts and for permitting a supply of clean toweling to be withdrawn from the slot 34 by pull upon the front part 53 of the exposed loop of the towel. Inasmuch as the machine here shown is intended to be manually operated, a 25 plunger means 64, shown diagrammatically, has been provided for actuation of the release extension 52 of the locking cam.

Inasmuch as the length of clean toweling that may be drawn out of the box upon each release 35 of the locking cam is directly proportional to the length of the endless chain 46, it is observed that such length may attain great amounts, for supplying great lengths of clean toweling with each release of the locking cam, without requiring the 40 box to be of extraordinary size.

It is also observed that it is an easy matter to vary the length of towel supply that can be provided by each unlocking of the cam. In the construction here shown the endless chain is provided with but one stop, and consequently a release of the cam and a pull upon portion 53 of the exposed loop of the towel will supply an amount of clean toweling exactly equal to the sum of half of the circumferences of the rollers plus 50 twice the center to center distance between them.

If, however, two stops be used, each release of the locking cam will permit the supply of clean toweling in a length equal to one-half that length; and if three stops be used, the amount will be equal to one-third that length. It is contemplated to provide an assortment of chain formations and sprocket sizes so that the purchaser of cabinets may have the option of determining the length of clean towel supply permitted by each cam release and in addition it is contemplated to have the mountings for the rollers 20-30 made adjustable so that the lengths of the chains may be varied at the options of purchasers of the cabinets.

I claim:

1. In a roller towel cabinet construction, a toweling dispensing mechanism comprising a toweling measuring roller, a toweling rewinding roller, an endless sprocket chain connected to and interconnecting said rollers, a link on said sprocket chain having a stop lug projecting laterally therefrom, a pivoted bell crank locking cam, a locking portion projecting therefrom for intercepting the movement of said stop lug on said sprocket chain, manually actuatable means for moving said locking portion to release said stop lug, and means for automatically restoring said locking portion for intercepting the movement of the stop lug on the sprocket chain. 25

2. In a roller towel cabinet construction, a toweling dispensing mechanism comprising a toweling measuring roller, a toweling rewinding roller, an endless sprocket chain connected to and interconnecting said rollers, a link on said sprocket chain having a stop lug projecting laterally therefrom, a pivoted bell crank locking cam, a locking portion projecting therefrom for intercepting the movement of said stop lug on said sprocket chain, a manually actuatable release extension on said bell crank locking cam for moving said locking portion to release said stop lug, means for automatically resetting said locking portion for intercepting the movement of said stop lug, a shoulder pin projecting laterally from said release extension, and a spring engaging said shoulder pin for holding said bell crank locking cam in reset position after it has been automatically restored thereto. 40 45

BEN H. BELENSON. 50.
